UNITED STATES PATENT OFFICE.

LOUIS RENARI, OF SANTA ROSA, CALIFORNIA.

COMBINATION RIM TOOL AND JACK.

Application filed March 29, 1927. Serial No. 179,297.

This invention relates to improvements in appliances for use in connection with the operation of motor vehicles. My principal object is to provide as a single unit a tool which may be efficiently used as a jack for any purpose, such as raising or lowering a wheel of a motor vehicle for making tire changes; which may be also used for expanding and contracting the usual split demountable tire rims; and also as a powerful appliance for pulling any one element toward another.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a longitudinal elevation of my improved tool as applied to a split rim to contract the same.

Fig. 2 is a sectional elevation of the tool detached.

Fig. 3 is a view of the tool as applied to expanding a rim.

Referring now more particularly to the characters of reference on the drawings, the numeral 1 denotes a barrel of tubular form having a bore 2 extending from one end thereof to a point short of the other end. The outer end of the bore terminates in a tapped portion 3 of somewhat smaller diameter than the bore, while the opposite end of the barrel has a tapped hole 4 considerably smaller than the tapped portion 3 and communicating with the bore 2. Screwed into the portion 3 and normally projecting into the bore is a hollow screw stem 5 having a base pad 6 on its outer end. Screwed into the tapped portion 4 is another screw stem 7 of a size such as to enable it to telescope into the stem 5 and having a pad 8 on its outer end. When the stems are fully telescoped into the barrel and into each other, the total length of the device between the outer faces of the opposed pads is but little greater than that of the barrel itself, so that the device is very compact and may be used in connection with cars having balloon tires whose axles when the tires are flat are somewhat close to the ground. Owing

to the telescoping of one stem into the other the total length of the structure when the stems are separated as far as possible may be nearly double the length of the jack when the stems are contracted.

One stem is threaded right-hand and the other left-hand and the pitch of the threads is the same. It will therefore be seen that if the barrel is rotated the stems will be moved in or out relative to the barrel an equal distance simultaneously. In order to prevent one stem turning relative to the other, so as to insure uniformity of movement, the stem 7 is provided with a square or polygonal sided bore 9 in which is slidable the similarly shaped head 10 of a stem 11 which is secured at its opposite end in the pad 6 of the stem 5. This stem is of such a length that it will not interfere with the full stroke of the stems away from each other. Various mechanisms may be provided for rotating the barrel to effect the above movement of the stems. In the present instance I mount a bevel gear 12 on the barrel which engages a bevel pinion 13 which in turn is mounted in a housing 14 turnably disposed about the barrel but fixed against movement longitudinally thereof. This pinion is provided with a socket member 15 or the like outside the housing so that a turning implement of any character and length may be detachably applied thereto.

Projecting outwardly from the opposite sides of the pads 6 and 8 in longitudinal alignment with each other are orificed lugs 16 to which may be removably attached one end of short independent chains 17, the outer ends of which carry hooks 18. These hooks are particularly shaped to be engaged with the side flanges of a demountable rim 19, at diametrically opposed points thereon.

In operation, for use as a jack the opposed pads of the device are engaged with the ground and with the axle or other part of the car respectively, and a rotative movement is applied to the pinion 13 to cause the barrel to be rotated and the stems to be raised or lowered as the case may be.

When the device is used to contract a rim the stems are first advanced somewhat and the hooks are then attached to the rim at opposed points and on both sides thereof, one pair of such hooks being disposed near the split S of the rim and of course engaged with that portion of the rim which is to be drawn inwardly. If then a retractive or telescopic

ing movement is imparted to the stems the rim will be drawn inwardly by the pressure thus applied to the chain hooks, as will be evident. When using the tool to expand the rim back into place I preferably lay a cross timber as at 20 in the rim in a suitable position and rest one pad against the timber while the other pad bears against the rim at such a position that an outward movement of the stems will cause the rim to be forced outwardly and into place. By means of the chain and hook arrangement the tool may be also used in certain cases in place of a block and tackle structure, as will be obvious.

The hooks are of such form that any desired number of links of the chain may be taken up and engaged with the hooks, so as to shorten the operative lengths of the chains to any desired degree.

From the foregoing description it will be readily seen that I have produced such a device as substantially fulfills the objects of the invention as set for herein.

While this specification sets forth in detail the present and preferred construction of the device, still in practice such deviations from such detail may be resorted to as do not

form a departure from the spirit of the invention, as defined by the appended claims. 30

Having thus described my invention what I claim as new and useful and desire to secure by Letters Patent is:

1. A jack including a barrel, a screw stem threaded therein from one end, another screw stem arranged to telescope into the inner end of the first named stem from the inner end and threaded into the opposite end of the barrel, the threads on the stems being cut in opposite directions to each other, means for rotating the barrel, and a stem fixed in the first named screw stem at its outer end and projecting lengthwise into the last named screw stem from the inner end thereof in slidable but nonturning engagement therewith. 40 45

2. A structure as in claim 1, in which the bore in the screw stem into which said fixed stem projects is larger than said fixed stem except at the inner end of the screw stem, 50 and the fixed stem has a head on its outer end movable in the larger portion of the bore.

In testimony whereof I affix my signature.

LOUIS RENARI.
